Patented Dec. 14, 1920.

Fig. 2.

UNITED STATES PATENT OFFICE.

WILFRED E. BOOTH, OF NEW YORK, N. Y., ASSIGNOR TO WESTERN ELECTRIC COMPANY, INCORPORATED, OF NEW YORK, N. Y., A CORPORATION OF NEW YORK.

RADIO-CABINET.

1,361,818.

Specification of Letters Patent. Patented Dec. 14, 1920.

Application filed July 19, 1917. Serial No. 181,594.

To all whom it may concern:

Be it known that I, WILFRED E. Booth, a citizen of the United States, residing at New York, in the county of New York and 5 State of New York, have invented certain new and useful Improvements in Radio-Cabinets, of which the following is a full, clear, concise, and exact description.

This invention relates to radio apparatus, 10 and more particularly to cabinets which are adapted to accommodate radio sending and receiving sets.

An object of the invention is to provide a unitary structure containing a radio sending and radio receiving set in which the various parts of each set may be easily inspected, repaired or replaced, and to so arrange the terminals for each set as to facilitate making the necessary electrical connections for the sets.

This is accomplished by mounting these sets to be independently removable from the cabinet so that access may be had to either set without disturbing the other. The sets 25 are so mounted within the cabinet as to leave a space at the front of the cabinet therebetween into which the terminals from each set project. This provides for conveniently making the connection between 30 one set and the other set and also between the sets and the antenna.

Referring to the drawings:

Figure 1 illustrates a front elevation of the cabinet, a portion of which is broken away to show the terminals for each set;

Fig. 2 illustrates a side elevation of the cabinet having portions broken away to show a cross-section and details of the terminal boards;

Fig. 3 shows a detail of the terminal board; and

Fig. 4 shows a form of connector that may be used.

In Figs. 1 and 2 the cabinet 5 is adapted 45 to be supported by suitable means, such as legs 6, and is provided with a shelf 7 at a proper height for the operator's convenience. Cabinet 5 is made in two sections 8 and 9, the former section being removably 50 mounted on the bottom section 9. Removably mounted within the section 8 is a radio receiving set having the front instrument board 10, which is flush with the front of the cabinet 5. Integrally mounted on the instrument board 10 is the 55

terminal board 11 of insulating material on which are mounted the terminals 12, which are connected to the radio receiving set.

As shown in Fig. 3 the terminal 12 is 60 fastened to terminal board 11 by a screw 27. Electrical connection is made from lead 28 to one end of terminal 12 by the bolt 29 and nut 30. Connector 15 is clamped to the other end of terminal 12 by means of 65 a screw 31.

The shelf 13 and terminal board 11 provide a supporting base upon which the radio receiving set is mounted. The angle strip 21 is fastened to the back of the instrument board 10 and to the under side of shelf 13 and terminal board 11. The bottom of that portion of strip 21 which is beneath terminal board 11 and shelf 13, is in sliding contact with the top of a strip 22 fastened 75 to section 8. Fig. 1 shows the strip 22 at one side of the cabinet and a similar strip not shown is provided at the other side. The front end of strip 22 and the front end of a similar strip 23 fastened to section 9, 80 are bent into a vertical plane so that a strip 24 may be fastened thereto. The strip 24 at the left side of the cabinet and a similar strip, not shown, at the other side provide a support for a cover 14, a screw 25 passing 85 through each end of cover 14 into the threaded aperture 26 in each of the strips 24. The receiving set including the instrument board 10, the terminal board 11 and the shelf 13 is freely removable from the 90 section 8 when the cover 14, connectors 15 and strips 24 are removed, each of the strips 21 sliding on the strips 22.

The radio sending set has an instrument board 16 which defines a portion of the 95 front of the cabinet. Suitably fastened to the instrument board 16 is the terminal board 17 to which the connections for the sending set are brought, the terminal board 17 being provided with terminals 18, similar to the terminals 12. The board 32 is fastened to section 9 and extends across the top of the same to protect the apparatus below it. Fastened to the bottom of instrument board 16, by means of strips 36, is a 100 board 33 which extends across the bottom of section 9 and which supports the sending set. The board 33 slidably engages at each end a strip 34 which is fastened to and 105 raised above the bottom 35 of the cabinet. 110

The shelf 7 is held in position by means of the braces 37 and thumb nuts 38 which are threaded on bolts fastened to the sides of the cabinet. Fastened to each side of 5 the shelf 7 is a strip 39 which is clamped by thumb nut 38 to hold the shelf 7 in position.

When the connectors 15, strip 24, cover 14 and shelf 7 are removed, the sending set 10 may be withdrawn from the cabinet without otherwise disturbing the receiving set.

When the radio sending and receiving sets are positioned within the cabinet a space is left between these two sets into 15 which the terminals 12 and 18 project. This makes it convenient to properly connect the sending and receiving sets by means of the connectors 15, while the connections from those sets to the antenna may be made from 20 the lugs 20 through the aperture 19 in the side of the cabinet.

It will be apparent that the sending and receiving sets are independently mounted within the cabinet 5, whereby either set may 25 be removed without disturbing the other, and, furthermore, because of the proximity of the terminal boards of the two sets, the necessary electrical connections for these sets may be easily made.

30 What is claimed is:

1. An electrical cabinet comprising a main inclosing casing, a cabinet section having electrical terminals positioned adjacent to the top of said section, a second cabinet 35 section having electrical terminals positioned adjacent the bottom thereof, said former section being adapted to support said latter section whereby said terminals of one section may come adjacent said terminals of the other section, said cabinet having 40 an aperture through which said terminals are accessible, and a closure for said aperture.

2. The combination of a cabinet, a radio 45 receiving set adapted to be inserted in said cabinet from one side thereof, a radio sending set adapted to be inserted into said cabinet adjacent to said receiving set, each of said sets having a terminal board with extending terminals, and supporting means 50 within said cabinet for positioning said ter-

minal boards adjacent to but spaced from each other.

3. The combination of a cabinet having an open side, a radio sending set and a radio 55 receiving set adapted to be positioned within said cabinet, each of said sets having instrument boards which are adapted to cooperate to substantially close the opening in said cabinet when said sets are positioned 60 within said cabinet.

4. The combination of a cabinet having a radio sending set and a radio receiving set mounted therein, each of said sets having terminals for making electrical connections 65 and also having instrument boards which define the front of said cabinet, there being a space between said sets, said terminals projecting into said space, and a cover for said space.

5. Radio apparatus including a plurality of units, connecting terminals on parts of said units respectively which are adapted to be placed adjacent to and facing one another, means for spacing said units whereby 75 said terminals are brought into immediate proximity, and a cabinet having guides for receiving said units and concealing and protecting said terminals.

6. Radio apparatus including a plurality 80 of units, connecting terminals for each unit, and means for connecting said terminals to an adjacent unit, a cabinet having guides for receiving said units, instrument boards on said units for substantially closing the opening in said cabinet, and a closure board for closing the otherwise open portion of said opening.

7. Radio apparatus including a plurality 85 of units, connecting terminals for each unit, 90 means for connecting said terminals to an adjacent unit, said terminals and said means being confined within the planes defining extreme limits of said units when said terminals are connected, integral parts on said 95 units for partly inclosing said terminals and connecting means, and an additional element for completing said closure.

In witness whereof I hereunto subscribe my name this 13th day of July, A. D. 1917. 100

WILFRED E. BOOTH.
